COIN CONTROL FOR SCALES

Filed Aug. 5, 1935

1.

FIG. 2.

INVENTOR:
WILLIAM R. McDONALD,
By: Otto D. Ringer,
his Atty.

UNITED STATES PATENT OFFICE

2,029,269

COIN CONTROL FOR SCALES

William R. McDonald, Los Angeles, Calif., assignor to L. H. Stark, Los Angeles, Calif.

Application August 5, 1935, Serial No. 34,706

2 Claims. (Cl. 194—47)

This invention relates to devices used on weight indicating apparatus, such as scales.

One of the objects of this invention is to provide means for preventing the repeated use of a scale by means of a single coin or similar token.

Another object is to provide mechanisms whereby a coin or token can be made to free a scale for operation either before or after matter is placed on the scale.

Another object is to provide means whereby the coin actuated parts are automatically returned to inoperative position on even a short return of the weight-supporting platform.

Another object is to provide means whereby the indicating mechanism is automatically locked when the coin control becomes inoperative.

Other objects will appear from the following description and appended claims as well as from the accompanying drawing, in which—

Fig. 1 is a fragmentary illustration of scale mechanisms in operative connection with a coin control according to this invention.

Fig. 2 is a fragmentary illustration with the coin control in actuated position.

Material to be weighed is commonly placed on a platform, and platforms are designed according to what is to be weighed, but all such platforms are commonly connected to some sort of indicator or indicating mechanism by some sort of connecting rod, such as indicated at 3 in Fig. 1.

Such connections also must necessarily depend on various arrangements of different scales and the rod 3 shown here of a certain form may nevertheless be of a different form according to other details or parts of different scales.

As illustrated, this arrangement refers to scales in which the rod 3 is suspended from suitably adjusted springs 4 that become stretched according to the platform supporting mechanism or lever arrangement, not shown in the drawing, there being an abutment 5 associated with the rod 3 to become spaced from a follower member 6 according to the movement of the rod and platform.

The follower 6 is customarily in operative connection with an indicator mechanism by which the weight placed on the platform may be ascertained.

Platform mechanisms and indicators are so well known as to not require further illustration and in this case are not to be claimed as a part of the invention, only enough being therefore shown of such mechanisms that their relation to the parts of the present invention may be visual-

ized, and it must be understood that this invention is not meant to be limited to the association with such illustrated or indicated parts.

The follower 6 is in this case provided with a gear rack 7 in engagement with a gear 8, which, in turn, forms a part together with the ratchet wheel 9 of a rigidly assembled unit for controlling the rotation of an indicator.

The inventor also does not limit himself to the specific form, or appearance of any indicator, or its further operative connection to the follower, since of no material consequence as far as this invention is concerned.

It will readily be understood that the rotating movements of the rear 8 and ratchet wheel 9 can easily be utilized for operating any indicator.

Any attached indicator is held against movements as long as the gear 8 and the ratchet wheel are held by the pawl 10; while on the removal of the pawl the gear 8 and the ratchet wheel are free to move, the follower 6 forming the means of rotating the gear 8 and the wheel 9 by merely dropping to the extent of the space between the follower and the abutment 5, a greater weight on the platform of a scale, creating a larger space between the abutment 5 and the follower 6, resulting in a greater movement of the connected indicator by means of the gear 8 and the ratchet wheel 9 as long as the pawl is removed.

For removing or releasing such a pawl, with scales placed for public use, coin controlled mechanisms are commonly applied, and it has become a feature to provide means against a double use of the scale by means of a single coin.

With the arrangement illustrated in the drawing, a coin may be dropped through the chute 11 to hit the trap door 12 so that this door that is pivotally mounted at 13 may move to the position indicated at 12a in Fig. 2, a lever portion 14 being provided at the opposite side from the pivot to form a counterbalancing means for the door 12 by which the door is inclined to return to its inoperative position in which it is illustrated in Fig. 1.

The overbancing lever 14 is connected to the lowermost end 15 of another lever 16 by the link 17, the lever 16 being pivotally suspended at 18 and supporting the pawl 10 on the pin 19.

A spring 20 serves to move and hold the pawl 10 in the direction towards the ratchet wheel 9, a stop-pin 21 serving to hold the pawl against excess movements when the pawl is removed from the ratchet wheel.

By the tilting of the coin trap door 12 the

lever 16 is brought to the position illustrated in Fig. 2 by means of the link connection, thereby bringing the pawl to disengaged position with respect to the ratchet wheel, to result in the freeing of the gear 8 and the ratchet wheel 9 and thereby of the follower 9, to function as set forth above.

In order that the follower may drop unchecked to contact with the abutment 5, the coin trap door, of course, must be prevented from returning to inoperative position too quickly by means of the counterbalancing lever 14 or thereby to bring the pawl into engagement with the ratchet wheel 9 before the follower has reached such contacting position.

The spring 22 is therefore securely mounted on the lever 14 in a certain position so that its end 23 comes into locking position with a notched wheel 24 as soon as a coin or similar token has actuated the trap door as set forth.

From this position the trap door can only be released by a turning of the wheel 24 in the direction of the arrow 25, against which, however, the wheel is held by the notched rod 26.

The notch-engagement between the wheel 24 and the rod 26, regardless, is very slight, since the trap door 12 will readily return to its inoperative position by means of its own counterbalancing lever 14 if only helped to pass the wheel sufficiently so that the wheel is not directly against the end of the spring 22, and the notch engagement is not required to overcome any particular force, the spring itself being of a very light material, the rod 26 being loosely pivoted at 27 to any part of the platform connecting rod 3 so that the rod 26 will readily follow the up and down movements of the platform as well as change its slightly varying slanting position and still maintain its notching contact with the wheel 24.

As long as the rod 3 is stationary by the fact that a connected platform is held down by any material placed thereon, the trap door will also be held stationary, but the slightest upward movement of the rod 3, or even any vibration, as by any jumping on the platform of a personal scale, the wheel 24 will eventually be turned sufficiently to allow the spring 22 to disengage itself from the wheel 24 and thereby release the trap door 12 to inoperative position. Any further jumping on the platform will just merely lift the follower and thereby hold the indicator above the jumping or vibration caused uppermost position and not furnish any further correct weight indication.

On a full return of the rod 3 to its uppermost position the follower also will just naturally be returned to its uppermost position and therewith any attached indicator to its inoperative position.

A new coin or token must then necessarily be inserted first before any further indication can be obtained.

From the above and from the illustration it should also readily be understood that a coin or token may be inserted equally well before or after any material is placed on any scales to which this arrangement is applied, since any downward movement of the platform, as represented by the rod 3, and thereby any downward movement of the rod 26 does not in the least affect any of the operations of the trap door 12 or any of the parts that affect the closing of the trap door, since the spring end 23 will merely rattle lightly over the notch ends of the wheel 24 when the wheel

is turned in the opposite direction of the arrow 25.

It will be noticed that the link connection between the link member 17 and the lever 14 is somewhat beyond dead center position, eventually not necessary but serving to help in the adjustment for the weight of different coins, so that the trap door must eventually be operated against the tension of the pawl spring 20.

Tensions can furthermore be adjusted by the adjustment indicated at 28, by which the lever 16 can be lowered or raised generally so as to change or influence of the link position at 17 in Fig. 1; and another adjustment indicated at 29, by which the pivot 13 and therewith the whole trap door can be moved back and forth in a sidewise direction, eventually increasing the tension of the spring 20 on the operation of the trap door.

Having thus described my invention, I claim:—

1. In a weighing device, a coin chute, a weight ascertaining mechanism including a gear pinion and a ratchet wheel securely combined for rotation around a common axis, a coin trap pivotally mounted with respect to the chute to be actuated by a coin passing through the chute, a counterweight portion on the coin trap extending beyond the pivot mounting for returning the coin trap to and normally maintaining it in inoperative position, a ratchet pawl support pivotally mounted with respect to the coin trap, a ratchet pawl pivotally mounted on said support under spring tension that normally allows said pawl to rotate in one direction only, locking against movements in the opposite direction, said counterweight portion and link member functioning in manner of a toggle to fold when the trap is actuated by a coin so as to swing the connected suspended ratchet pawl support to such an extent that said pawl is withdrawn sufficiently to allow said weight ascertaining mechanism to move in said opposite direction, an operating member mounted for rotation subject to movements of a cooperatively connected weighing device, and a spring member with one end secured to the coin trap and with the other end disposed to become engaged with said operating member when the coin trap is actuated.

2. In a weighing device including a part extending upwardly from the movable supports upon which normally materials are placed for weighing purposes, a coin controlled indicating mechanism including a coin chute, a weight ascertaining mechanism including a gear pinion and a ratchet wheel securely combined for rotation around a common axis, a coin trap pivotally mounted with respect to the chute to be actuated by a coin passing through the chute, a counterweight portion on the coin trap extending beyond the pivot mounting for returning the coin trap to and normally maintaining it in inoperative position, a ratchet pawl support pivotally suspended at one end and with the other end extending to a point near said counterweight portion, a link member connecting the ratchet pawl support and counterweight portion, a ratchet pawl pivotally mounted on said support under spring tension that normally allows said pawl to rotate in one direction only, locking against movements in the opposite direction, said counterweight portion and link member functioning in manner of a toggle to fold when the trap is actuated by a coin so as to swing the connected suspended ratchet pawl support to such an extent that said pawl is withdrawn sufficiently to allow said weight ascertaining mechanism to move in said opposite direction, an operating member mounted for rotation subject to movements of a cooperatively connected weighing device, and a spring member with one end secured to the coin trap and with the other end disposed to become engaged with said operating member when the coin trap is actuated.

tate in one direction only, locking against movements in the opposite direction, said counter-weight portion and link member functioning in manner of a toggle to fold when the trap is actuated by a coin so as to swing the connected suspended ratchet pawl support to such an extent that said pawl is withdrawn sufficiently to allow said weight ascertaining mechanism to move in said opposite direction, an operating member 5 mounted for rotation and having engaging means, a control member with one end pivotally connected to said first-named part and having en-

gaging means for rotating said operating member by the up and down movements of the movable supports of a weighing device, and a spring member with one end secured to the coin trap and with the other end normally disposed free 5 of engagement and adapted to become engaged with said operating member when the coin trap is actuated to be set free again by any upward movement of said part subject to upward movements of the movable supports of the weighing 10 device.

WILLIAM R. McDONALD.
